CLAIM

The ornamental design for a digital media player dock with alarm clock, as shown and described.

DESCRIPTION

FIG. 1 is a top, front, side, perspective view of a digital media player dock with alarm clock showing my new design;

FIG. 2 is a front view thereof;

FIG. 3 is a rear view thereof;

FIG. 4 is a top view thereof;

FIG. 5 is a bottom view thereof;

FIG. 6 is a side view thereof, the opposite side view being a mirror image; and,

FIG. 7 is a cross sectional view thereof along the line 7—7 in FIG. 2.

The broken line showing is of environmental material and forms no part of the claimed design.
